INVENTOR

WILLIAM S. RAWSON.

BY
Louis A. Bisson.

ATTORNEY

Patented June 30, 1925.

UNITED STATES PATENT OFFICE.

WILLIAM S. RAWSON, OF SPRINGFIELD, MASSACHUSETTS.

SOCKET.

Application filed January 30, 1922. Serial No. 532,925.

To all whom it may concern:

Be it known that I, WILLIAM S. RAWSON, a citizen of the United States, residing at 94 Phoenix Terrace, Springfield, in the county 5 of Hampden, State of Massachusetts, have invented certain new and useful Improvements in Sockets; and I do hereby declare the following to be a full, clear, and exact description of the invention, such as will 10 enable others skilled in the art to which it appertains to make and use the same.

The present invention relates to sockets of the kind capable of receiving automobile curtain supports, and particularly to the 15 structure of the socket.

Heretofore, it was customary to form sockets provided in automobile doors to receive the lower end of curtain supporting rods, without any closures, when the supporting 20 rods were removed, but in some cases, closures in the form of plates or covers hinged to the socket member were provided. That portion of the supporting rod which extended into the socket usually was smaller than the 25 space formed in the socket member with the exception, in some cases, of the upper end of the socket member which fitted more closely to that part of the rod. Although a cover, whether hinged or otherwise connected, may 30 have been used, such cover was not automatic in its closing action and was frequently left open so that foreign material readily entered the socket member and clogged it to the extent that the curtain supporting rods 35 could not be inserted in place. This type of closure also made it easy for malicious persons to insert foreign matter in such sockets with like results. There was, heretofore, no 40 device which would act automatically to close the socket opening and also to eject foreign material, if any were introduced in the socket, and also to maintain such socket 45 free of such matter.

In accordance with this part of my invention, the socket member has a passage which is preferably of uniform cross-sectional area throughout its length, a cover or member for such passage, preferably being a plunger 50 slidable in such passage and of substantially the same cross-sectional area, and means to limit the movement of this member. In this way the slidable member, in any of its positions in the passage of the socket member, closes the passage to the entry or passage 55 of foreign matter to the rear of the sliding member. Whatever matter may

have been introduced in the passage, when the sliding member is depressed will immediately be ejected as the sliding member returns toward the outer end of the passage. The means for limiting the movement of the sliding member acts to stop the outward movement of the sliding member with its outer surface flush with the outer 60 end surface of the socket member, so that any foreign matter, resting upon the top surface of the sliding member, may be easily brushed aside or wiped off without possibility of its entering into the socket member. 65 This limiting means may be adjustable and preferably comprises a rod fastened to the slidable member, together with adjustable means engaging with the socket member for limiting the outward movement of the 70 sliding member.

The passage may be of non-circular cross-section, preferably of polygonal form. The socket member also has means, preferably a flange which may extend laterally from the 75 socket member, by which the socket member may be fastened to the door of an automobile.

In a specific construction the socket member is located in the door of an automobile and has a passage open at its outer end and 80 closed at its inner end, the shank of the curtain rod being slidable in such passage. A plunger slidably fits in this passage and is movable inwardly, movable against spring 85 compression when the rod is inserted in the passage and movable outwardly by the compressed spring when the rod is removed from the socket member. A rod is connected to the plunger and engages with the socket 90 member for limiting the outward movement 95 of the plunger, so that the outer faces of the plunger and socket member are flush.

In the accompanying drawing illustrating a few embodiments of the invention in application, as an example, to an automobile 100 door and a curtain supporting rod cooperative therewith:

Fig. 1 is a sectional view of the socket and part of an automobile door; Fig. 2 is a top plan view thereof with the curtain supporting rod removed; Fig. 3 is a perspective view of the socket member when removed from the door; Fig. 4 is a sectional view of an optional form of socket; Fig. 5 is a sectional view taken on line 5-5 of Fig. 4; Fig. 6 is 105 a sectional view of another embodiment of the invention; Fig. 7 is a side view of still 110

another form of the invention; Fig. 8 is a top plan view of the same, but showing the door in section; Fig. 9 is a fragmentary side view of still a further form; and Fig. 10 is a top plan view of a triangular socket.

Referring more specifically to the drawings, and particularly to the form shown in Figs. 1, 2 and 3, the socket comprises a cylindrical socket member 1 inserted into a similar bore formed for it in a door 2 of an automobile. The member 1 has a square longitudinal bore of substantially uniform cross-section throughout its length, the socket member being open at its upper end but formed with a flange 3 at its lower end to substantially close such end. From the socket member 1 laterally extends an integral flange 4 suitably apertured for the insertion of wood screws 5, securing the socket to the door. To the upper edge of the door is fastened a cleat 6 by screws 7, the cleat operating to cover the flange 4 and give a finished top to the door. The upper end of the socket member terminates flush with the top surface of the cleat 6.

Within the passage of the socket member 1 is located a slidable plunger 8 to which is rigidly fastened a rod 9 extending through the flange 3 of the member 1. The cross-sectional area of this plunger is substantially the same as that of the passage in the member 1. The lower end of the rod 9 is threaded to carry an adjusting nut 10, bearing against the lower face of the flange 3, and a lock nut 11. Surrounding the rod and within the passage of the socket member is located a helical spring 12 reacting at one of its ends against the inner face of the flange 3, and at its other end against a leather washer 13 beneath the cover or plunger 8. The leather washer acts to prevent noise and rattling. The position of the nut 10 on the rod 9 limits or determines the upward movement and normal position of the cover or plunger 8 with respect to the top of the door. This nut 10 is so adjusted that the top surface of the plunger 8 will be flush with the upper surface of the cleat 6.

The curtain is supported upon a rod 14 in a known manner, and this rod has at its lower end a bent shank 15 having a squared lower end of substantially the same cross-sectional area as the passage in the member 1, and as the plunger 8. When the rod 14 is inserted in place with its lower end fitting in the passage of the socket member 1, the plunger 8 is lowered against the compression of the spring 12. The weight of the rod with that of the attached curtain is greater than the upward thrust of the spring, so that there is no tendency to cause the rod to work loose or out of the socket.

The door also has a small bore 16 into which the lower end of the rod 9 and the nuts 10 and 11 play when the plunger is de-

pressed upon the insertion of the curtain rod into the socket.

When the rod 14 is removed from the socket, the plunger 8 immediately moves upwardly to its normal position, the expansion 70 of the spring 12 effecting such. The nut 10 abuts the lower end of the socket member 1 just as the top surface of the plunger 8 comes flush with the top surface of the cleat 6. Inasmuch as the plunger 8 is of substantially the same cross-sectional area as the passage in the member 1, it has a sliding fit therein throughout the length of the passage, so that if any foreign matter should enter the passage when the plunger 80 is depressed, such matter cannot enter behind the plunger 8 or work its way past it, but will be carried upon the top surface of the plunger and ejected, when the plunger comes to normal position, so that it can be 85 easily wiped or brushed off.

While Figs. 1, 2 and 3 show a socket with a passage and plunger of square cross-section, it is to be understood that any other form of cross-section may be used, such as 90 a triangular cross-section, as shown in Fig. 10 of the drawing.

In Figs. 7 and 8, the socket comprises a substantially cylindrical member 17 having laterally extending side flanges 18 and 19, 95 adapted to be fastened to a vertical wall of an automobile door by screws 20. In order that the socket may be hidden from view, except at its upper end, a side panel 21 is fastened to the door and is formed to fit 100 over the socket member 17 and the flanges 18 and 19. The door otherwise comprises tongued and tenoned members 22 and 23 and an edge cleat 24. In other respects the socket is of the same construction as that 105 shown in Figs. 1, 2 and 3.

In Figs. 4 and 5 the means for limiting the upward movement of the plunger 8 is of telescopic form and comprises a tubular rod or member 25 and a solid rod 26, capable of sliding into the member 25. This provides for a shorter bore in the door than that required in the forms shown in Figs. 1, 2, 3, 7 and 8, no lower bore for the play of the lower end of the rod, connected to the plunger, being necessary. The tube 25 is threaded at its lower end and is adjustably connected to a ring nut 27 threaded into the lower end of the cylinder 28, the tube 25 having a suitable screw driver slot 29 for aiding in adjusting the relation of the tube with respect to the member 28, and the nut 27 having suitable spanner wrench recesses for the securing of the nut in the member 28. The upper end of the tube 25 is spun inwardly so as to form an annular shoulder 30, overhanging a ball 31 fastened to the lower end of the rod 26. The latter is secured, at its upper end, to the plunger 8, 125 as in the form shown in Figs. 1, 2 and 3. 130

A helical spring 32 extends between the nut 27 and the plunger 8 and surrounds the tube 25 and the rod 26.

When the curtain supporting rod is inserted into the socket member 28, and the plunger 8 depressed, the ball 31 slides downwardly in the tube 25, while compressing the spring 32. When the curtain supporting rod is removed, the spring forces the plunger 8 upward until the ball 31 hits against the shoulder 30, thus limiting the upward movement of the plunger. In order to have the plunger 8 stop flush with the top surface of the door, the tube may be rotated by a screw driver the required amount to locate the shoulder 30 at the proper stopping position.

In Fig. 6 a chain 33 is fastened to a screw-eye 34 fixed to the plunger 35, and to a bolt-eye 36 passing through the lower end 37. The latter carries an adjusting nut 38 and a lock-nut 39. In order that the plunger 35 may run square in the passage of the socket member, the plunger has a perimetral groove 40. A helical spring 41 extends from the plunger 35 to the bottom 37 of the socket member. When the curtain supporting rod is inserted and the plunger depressed, the chain 33 becomes slack and the spring 41 compressed, and when the rod is removed, the spring raises the plunger and the chain straightens out. In order that the upper surfaces of the plunger 35 may become flush with the top surface of the door, the nut 38 may be adjusted along the bolt 36 to effect a lengthening or shortening of the effective length of the chain. The lock-nut 39 is then tightened to lock the adjustment.

In Fig. 9, the lower end portion 42 of the curtain supporting rod carries a laterally extending pin 43, which is adapted to ride through a bayonet slot 44. This form of lock is used when the lower end of the rod is circular, so as to prevent the turning of the rod in the socket. In this case the spring 45, bearing upwardly against the plunger 46, is of greater strength than the combined weight of the rod and the curtain for the purpose of holding the pin 43 in locked position. Otherwise, the socket construction is similar to that shown in the other figures and described above.

While I have herein described and, on the drawing, illustrated a few embodiments of the invention, it is to be understood that the invention is not limited to the particular arrangement of parts and details shown and described, but that other arrangements of parts and details are comprehended, as do not depart from the scope of the appended claims.

Having thus described my invention what I claim is:

1. A socket device for automobile curtain

supports, comprising a socket member having a plunger passage, a plunger non-rotatably and slidably fitting in said passage and carrying a projection cooperable with an end of said socket member for limiting the movement of said plunger at an end of said passage, yieldable means for permitting the sliding of said plunger in said passage when a support is inserted in the socket member and to automatically move said plunger to the end of said passage when said support is removed from said socket member.

2. A socket capable of receiving an automobile curtain support and comprising a socket member having a passage, a plunger normally closing an open end of said passage and slidable in said passage upon insertion of said support in said passage and means between said plunger and the end of the socket remote from the open end thereof for limiting the movement of said slideable member at closing position thereof.

3. A socket capable of receiving an automobile curtain support and comprising a socket member having a passage, a member normally closing an open end of said passage and slidable in said passage upon insertion of said support in said passage, a spring for returning said member to closing position when said support is removed from said passage and means movable with said slideable member and engaging the socket member at the end thereof remote from the open end thereof for limiting the movement of said slideable member at closing position thereof.

4. A socket capable of receiving an automobile curtain support and comprising a socket member having a passage, a member normally closing an open end of said passage and slidable in said passage upon insertion of said support in said passage, and a spring for returning said member to closing position when said support is removed from said passage, and means cooperable with a part of said socket member remote from the open end thereof for limiting the outward movement of said member.

5. A socket device for automobile curtain supports, comprising a socket member having a passage of uniform cross-sectional area throughout the length thereof, a non-rotatable sliding member fitting in said passage and being of substantially the same cross-sectional area of said passage, a spring in said passage and acting against said sliding member to move it to the end of said passage whereby it may be substantially flush with the end of said socket member, and a projection movable with said sliding member and in said passage and contacting with an end portion of said socket member for limiting the movement of the sliding member in said flush position but permit-

- ting the movement of said sliding member cross-sectional area throughout the length and said projection in said passage upon the thereof, a member slidable in said passage insertion of said support in said socket and being of substantially the said cross-member.
5. 6. A socket device for automobile curtain erable to move said slidble member toward supports, comprising a socket member hav- 707
ing an end of said passage, and a slidble ele-
ment fitting in said passage acting against an end of said socket
said passage, a spring operable against said member for limiting the movement of said slider to move it toward an end of said passage whereby
10 10. 11. A projection extending from said said slidble member may stop flush with slider and movable in said passage and co- an end of said socket member
operable with an end portion of said socket
member for limiting the movement of said
15 15. 16. A slider substantially flush with an end of said socket member having a passage of uniform
said passage.
7. A socket device for automobile curtain thereof, a member slidble in said passage supports, comprising a socket member hav- and being of substantially the said cross-
ing a passage of uniform cross-sectional sectional area as said passage, a spring op-
area throughout the length thereof, a erable to move said slidble member toward
20 20. 21. 22. 23. 24. 25. 26. 27. 28. 29. 30. 31. 32. 33. 34. 35. 36. 37. 38. 39. 40. 41. 42. 43. 44. 45. 46. 47. 48. 49. 50. 51. 52. 53. 54. 55. 56. 57. 58. 59. 60. 61. 62. 63. 64. 65. 66. 67. 68. passage, said socket member having means intermediate the ends of said socket member capable of being fastened to a hidden part of the door of the automobile.

- 5 15. A socket capable of receiving an automobile curtain support and comprising a socket member having a passage of uniform cross-sectional area throughout the length thereof, a member slidable in said passage 10 and being of substantially the said cross-sectional area as said passage, a spring operable to move said slidable member toward an end of said passage, and means limiting the movement of said slidable member in 15 said passage, said socket member having intermediate its ends a laterally extending flange capable of being fastened to an inner part of the door of the automobile whereby said flange is hidden from view.
- 20 16. A socket capable of receiving the shank of an automobile curtain supporting rod and comprising a socket member located in the door of the automobile and having a passage open at its outer end and closed at 25 its inner end, said shank of said curtain rod slidably fitting in said passage, a plunger slidably fitting in said passage, a spring operable to move said plunger toward the open end of said passage upon the removal of said

shank from said passage and to become compressed upon the depression of said plunger when inserting said shank in said passage, and a rod connected to said plunger and engaging said socket member for limiting the outward movement of said plunger upon 35 the removal of said shank from said passage, whereby the outer surface of said plunger is flush with the outer end surface of said socket member.

17. A socket device for automobile curtain supports, comprising a socket member insertable in a body portion of an automobile and having an elongated passage for the reception of an end portion of a curtain support, a plug slidably fitting in said passage, a stop element movable in said passage and cooperating with said slidable plug and an end portion of said socket member for bringing the plug to a stop at an end of said passage when said support is withdrawn from said 50 socket member and for permitting said plug to slide along said passage when said support is inserted in said socket member, and means for automatically moving said plug to stopping position.

In testimony whereof I affix my signature.

WILLIAM S. RAWSON.
